UNITED STATES PATENT OFFICE.

ORLANDO L. WEAVER, OF AKRON, OHIO, ASSIGNOR TO THE STAR RUBBER COMPANY,
OF AKRON, OHIO, A CORPORATION OF OHIO.

DESIGN FOR A TIRE-CASING.

52,686.

Specification for Design. Patented Nov. 12, 1918.

Application filed June 12, 1918. Serial No. 239,683. Term of patent 14 years.

To all whom it may concern:

Be it known that I, ORLANDO L. WEAVER, a citizen of the United States, residing at Akron, in the county of Summit and State of Ohio, have invented a certain new, original, and ornamental Design for Tire-Casings, of which the following is a specification, reference being had to the accompanying drawings, forming a part thereof.

In the drawings,

Figure 1 is a plan view of a fragment of a tire casing showing my new design, and

Fig. 2 is a transverse section thereof on the line 2—2 of Fig. 1.

I claim:

The ornamental design for a tire casing, as shown.

In testimony whereof I affix my signature.

ORLANDO L. WEAVER.
